DESIGN FOR A TIRE RELEASING DEVICE

Walter F. Forsell, Minneapolis, Minn.

Application May 15, 1942, Serial No. 106,907

Term of patent 14 years

To all whom it may concern:

Be it known that I, Walter F. Forsell, a citizen of the United States, residing at Minneapolis, in the county of Hennepin and State of Minnesota, have invented a new, original, and ornamental Design for a Tire Releasing Device, of which the following is a specification, reference being had to the accompanying drawing, forming part thereof.

Fig. 1 is a side elevational view of a tire releasing device showing my new design;

Fig. 2 is a top plan view thereof;

Fig. 3 is a side elevational view disclosing the side opposite that shown in Fig. 1;

Fig. 4 is an end elevational view as the device would appear from the right side of Fig. 1; and

Fig. 5 is an end elevational view as the device would appear from the left side of Fig. 1.

I claim:

The ornamental design for a tire releasing device, as shown.

WALTER F. FORSELL,
